US00D949556S

(12) **United States Design Patent** (10) **Patent No.:** **US D949,556 S**
(45) **Date of Patent:** **** Apr. 26, 2022**

(54) **CONTAINER**

(71) Applicant: **L&F PLASTICS, CO., LTD.**, Miaoli County (TW)

(72) Inventor: **Mu-Chuan Hsu**, Miaoli County (TW)

(73) Assignee: **L & F Plastics Co., Ltd.**, Miaoli County (TW)

(**) Term: **15 Years**

(21) Appl. No.: **29/756,296**

(22) Filed: **Oct. 27, 2020**

Related U.S. Application Data

(62) Division of application No. 29/683,547, filed on Mar. 14, 2019, now Pat. No. Des. 919,972.

(57) **CLAIM**

The ornamental design for a container, as shown and described.

DESCRIPTION

FIG. 1 is a front perspective view of a container showing my new design;

FIG. 2 is a front view thereof and the rear view thereof being a same image;

FIG. 3 is a right side view thereof and the left side view thereof being a same image;

FIG. 4 is a top view thereof; and,

FIG. 5 is a bottom view thereof.

The broken lines in the figures show portions of the container that form no part of the claimed design.

1 Claim, 5 Drawing Sheets
